UNITED STATES PATENT OFFICE.

JOHN F. RUFF, OF PETERSBURG, INDIANA, ASSIGNOR OF ONE-FIFTH TO WALTER J. WILSON, ONE TWENTY-FIFTH TO JOHN M. WILSON, ONE TWENTY-FIFTH TO JOSEPH L. GRABLE, ONE TWENTY-FIFTH TO GEORGE M. WHITAKER, ONE TWENTY-FIFTH TO WILLIAM A. STONECIPHER, AND ONE TWENTY-FIFTH TO CHARLES E. STONECIPHER, ALL OF PETERSBURG, INDIANA.

ENSILAGE-REMOVER FOR SILOS.

1,174,524.

Specification of Letters Patent.

Patented Mar. 7, 1916.

Application filed March 18, 1915. Serial No. 15,288.

To all whom it may concern:

Be it known that I, JOHN F. RUFF, a citizen of the United States, residing at Petersburg, in the county of Pike and State of

5 Indiana, have invented certain new and useful Improvements in Ensilage-Removers for Silos; and I do declare the following to be a full, clear, and exact description of the invention, such as will enable others skilled 10 in the art to which it appertains to make and use the same.

My invention relates broadly to improvements in devices for lowering ensilage and the like, and more particularly to an apparatus of this class so constructed as to 15 allow one person to remove the necessary amount of ensilage.

The object of the invention is to provide a machine of the class set forth which, although 20 being of very simple construction and under the control of a single operator, will be very efficient in operation and will readily perform the functions for which it is designed.

25 With this object in view, the invention resides in certain novel features of construction and combination hereinafter described and particularly pointed out in the claim.

In describing the invention, I shall refer 30 to the accompanying drawings wherein like reference characters designate corresponding parts throughout the various views and wherein:—

Figure 1 is a side elevation of a portion 35 of a silo showing the application of the invention to use, all parts being shown in their normal positions; Fig. 2 is a similar view with the elevator car shown in raised position, and illustrating a pair of stop pins so disposed as to limit the upward and downward movement of said car; Fig. 3 is a vertical transverse section as seen along the plane indicated by the line 3—3 of Fig. 1; Fig. 4 is a horizontal section as seen along 40 the plane indicated by the line 4—4 of Fig. 1; Fig. 5 is an edge view of the invention.

In these drawings, constituting a part of the application, B designates a concrete base from which a common type of silo S rises, 45 this silo being provided at vertically spaced points with the usual doors D for removing the ensilage therefrom. The construc-

tion so far briefly set forth constitutes no part of the present invention, but is merely illustrated for the purpose of disclosing the 55 application thereof to use.

Rising from the base B and disposed in advance of the doors D, is a pair of upright parallel guide rails 1 whose lower ends are preferably anchored in said base, while their upper ends are connected by a pair of horizontal bars 2 which are secured thereto on opposite sides thereof, by bolts 3 or other appropriate fasteners. It will be noted that the bars 2 project laterally beyond one of the rails 1, and that these projecting ends carry bearings 4 in which the shaft of a pulley 5 is revolvably mounted, while the intermediate portions of the bars 2 carry similar bearings 4^a in which the shaft of an 60 additional pulley 5^a is revolvably mounted.

65 Mounted to slide vertically between the guide rails 1, is a car 6 which includes a horizontal platform 7 and an arched frame 8 rising therefrom, the cross bar 9 of this frame being provided with an eye-bolt or the like 10 to which one end of a cable 11 is secured, this cable being passed over the two pulleys 5 and 5^a and being secured to a weighted body 12 at its other end, such 70 body being of a weight greater than that of the car. In fact, the body 12 is of a weight sufficient to raise the car 6 and a person standing thereon to any desired position, in which position the car may be 75 frictionally locked by the provision of brake shoes 13 which are carried by the cranks 14 of a horizontal shaft 15, the latter being rotatably mounted in appropriate bearings 16 carried by the bar 9 and being provided 80 with a hand lever 17 forced downwardly by a coil spring 18, one end of which is secured to the lever 17 while its other end is anchored to one of the side bars of the arched frame 8. By the provision of the 85 spring 18, the shoes 13 are normally forced into contact with the guide rails 1, thus preventing the weighted body 12 from raising the car either from its lowermost position or from one of its raised positions, 90 wherein it is so disposed as to allow ensilage to be loaded thereon from one of the doors D.

In addition to the parts above described,

the sides of the car are provided with U-shaped guides 19 which slide upon the rails 1, these guides being disposed at any suitable points. Furthermore, a metal bar 20 is secured to the side of the bar 9 opposite the shaft 15, said bar 20 projecting beyond the ends of said bar 9 to provide additional friction shoes 21 which are forced to bind against the rails 1 when the shoes 13 are forced into contact with said rails.

As hereinbefore suggested, the car 6 normally stands in lowered position as shown in Fig. 1, in which position it is frictionally retained against the power of the body 12, by the brake shoes 13 and 21 above described. When, however, it is necessary to remove ensilage from the silo, the person wishing to operate the machine steps upon the platform 7 and pulls upwardly on the lever 17, thereby releasing the shoes 13 and allowing the weighted body 12 to move downwardly, thus raising the platform. During the upward movement of the latter, its speed and amount of travel is readily under the control of the operator who may allow the spring 18 to apply the shoes 13, when the necessary altitude is reached. He then positions a pair of stop members 22 here shown in the form of pins, in certain openings 23 with which one of the rails 1 is provided, said pins being then disposed above and below a stop member 24 which projects laterally from one side of the frame 8 past the openings 23. By this provision, it will be seen that under no circumstances can the car move either upwardly or downwardly. The operator now deposits a load of ensilage upon the platform 7 and, by releasing the brake shoes 13 and balancing the body 12 with the ensilage, he may ascertain the exact amount desired, provided the body 12 be of the correct weight. During this operation, it is essential that some stop means such as the pins 22 and the member 24 be provided, since were no such provision made, the moment the shoes 13 were released, the car would move either upwardly or downwardly according to the distribution of weight on the opposite ends of the cable. By the use of such stop means, however, it will be evident that the car is allowed only a small amount of movement which is necessary in order that the operator may ascertain when the weight of the ensilage on the platform balances the weight

of the body 12. He then applies the brake shoes 13, steps upon the platform 7 and releases said shoes an amount great enough to allow the car to travel downwardly at any preferred speed. When the car is in its lowermost position, the spring 18 is again allowed to apply the brake shoes 13, thus preventing the car from being moved upwardly by the body 12 after the ensilage has been removed.

From the foregoing description, taken in connection with the accompanying drawings, it will be evident that although comparatively simple construction has been provided for carrying out the object of the invention, the complete machine will be very efficient in operation and will possess a number of advantageous features. Particular emphasis is laid upon the provision of the stop pins 22 which are movable vertically to a number of predetermined points and which are insertible in any of the vertical series of openings 23 at points above and below the stop member 24, regardless of the altitude of the latter.

I claim:

In a load lowering apparatus, a pair of substantially squared upright parallel guide rails having a plurality of series of vertically spaced horizontal openings formed in one side of one of said guide rails, a normally lowered car comprising a horizontal platform and an arched frame rising therefrom, and movable vertically between the two guide rails, a stop member projecting laterally from one of the upright bars of said arched frame and extending beyond the aforesaid openings, a pair of stops movable vertically to a plurality of positions and insertible into the openings above and below the stop member on the car, whereby to limit both the upward and the downward movement of said car when loading the same, a pulley at the upper end of the rails, a cable passing over the pulley and secured at one end to the car, and a normally raised body secured to the other end of said cable and of a weight greater than that of the car.

In testimony whereof I have hereunto set my hand in presence of two subscribing witnesses.

JOHN F. RUFF.
